UNITED STATES PATENT OFFICE.

HENRY HERBERT HOWARD, OF NEW YORK, N. Y.

DESIGN FOR SCISSORS.

SPECIFICATION forming part of Design No. 19,029, dated April 9, 1889.

Application filed March 8, 1889. Serial No. 302,535. Term of patent 14 years.

To all whom it may concern:

Be it known that I, HENRY HERBERT HOWARD, a citizen of the United States, residing at New York, in the county of New York and State of New York, have invented a certain new and useful Design for Scissors, of which the following is a specification, reference being had therein to the accompanying drawing.

5 My newly-designed scissors are shown in open position in the accompanying drawing; and the leading features of my design consist of the rounded outer ends, *a*, of the blades 10 *b*, and the convex front or cutting edges, *c*, of

the said blades, the curves at the inward ends of said edges being on arcs which, if extended, 15 would pass near to or through the center of the pivot *d* of the blades.

I claim—

The design for scissors, as described and shown. 20

In testimony whereof I affix my signature in presence of two witnesses.

HENRY HERBERT HOWARD.

Witnesses:

HENRY CALVER,
A. V. CUSHMAN.
